UNITED STATES PATENT OFFICE

168,975

PLATE OR SIMILAR ARTICLE

Gerald S. Stone, Scarsdale, N. Y., assignor to
Johnson Bros. (Hanley) Limited, Hanley,
Stoke-on-Trent, England, a British company

Application June 24, 1952, Serial No. 20,340

Term of patent 14 years

(Cl. D44—15)

To all whom it may concern:

Be it known that I, Gerald S. Stone, a citizen of the United States of America, residing at 2 Broadmoor Road, Scarsdale, in the county of Westchester and State of New York, have invented a new, original, and ornamental Design for a Plate or Similar Article, of which the following is a specification, reference being had to the accompanying drawing, forming a part hereof.

In the drawing, Fig. 1 is a top plan view of a plate or similar article showing my new design, and Fig. 2 is a sectional view taken on the diameter thereof.

I claim:

The ornamental design for a plate or similar article, as shown.

GERALD S. STONE.
